UNITED STATES PATENT OFFICE

120,383

DESIGN FOR AN AIR COOLING AND DEHUMIDIFYING UNIT

Raymond Loewy, New York, N. Y.

Application May 24, 1939, Serial No. 85,183

Term of patent 14 years

To all whom it may concern:

Be it known that I, Raymond Loewy, a citizen of the United States, residing in New York, in the county of New York and State of New York, have invented a new, original, and ornamental Design for an Air Cooling and Dehumidifying Unit, of which the following is a specification, reference being had to the accompanying drawing, forming part thereof.

The figure is a side elevational view of an air cooling and dehumidifying unit embodying my new design. The unit is substantially round in cross-section and all sides present substantially the same appearance as the side shown.

The dominant features of my design reside in the portions shown in full lines.

I claim:

The ornamental design for an air cooling and dehumidifying unit, substantially as shown and described.

RAYMOND LOEWY.
